The ornamental design for a brush handle with sprayer, as shown and described.

DESCRIPTION

FIG. 1 is a left side elevational view of the brush handle with sprayer according to our new design, the right side elevational view being a mirror image thereof;

FIG. 2 is a front elevational view thereof;

FIG. 3 is a rear elevational view thereof; and,

FIG. 4 is a top plan view thereof, the bottom plan view being substantially plain and non-ornamental.

The broken line showing of the outline of a brush is for illustrative purposes and forms no part of the claimed design.
